(57) **CLAIM**

The ornamental design for a footwear upper portion, as shown and described.

DESCRIPTION

The design of the present application is directed to a footwear upper portion that can be used, for example, with a sole portion as a shoe.

FIG. 1 is a top and right front perspective view of a footwear upper portion, showing my design;

FIG. 2 is a left side elevational view thereof;

FIG. 3 is a top elevational view thereof;

FIG. 4 is a right side elevational view thereof;

FIG. 5 is a front elevation view thereof; and,

FIG. 6 is a rear elevational view thereof.

The phantom lines shown in the drawings are for illustrative purposes only and form no part of the claimed design.
